LOCKING DEVICE

Edward H. McCloud, Columbus, Ohio, assignor to
The Kinnear Manufacturing Company, Co-
lumbus, Ohio, a corporation of Ohio

Original application November 19, 1940, Serial No.
366,269. Divided and this application June 10,
1941, Serial No. 397,417

8 Claims. (Cl. 160—201)

The present invention relates to a grille or barricade, particularly such a grille as is adapted to be rolled up on a drum and serving to obstruct passageways, openings, etc. In order to close off certain passageways, such as elevator wells, gate openings in iron fences, openings in the front of a garage, etc. or to a bank vault, it is customary to provide a metal grille of considerable size which is adapted to be rolled up on a drum when entrance is desired, but can be securely locked in place to close off the passageway.

This application is a division of my prior application Serial No. 366,269 filed November 19, 1940.

A grille of this character was often made of complicated design, in the form of lattice-work made up of a large number of strip elements bolted or pivoted together. Ordinarily these elements are of a multitudinous number of shapes and sizes and are individually designed for each separate grille, depending on the size, shape and purpose of the grille. It is apparent that a grille of this character is quite expensive in that it was usually made to order and the parts cannot ordinarily be substituted for one another, and replacements are made only with great difficulty.

In order to lock the grille in place it has been customary to employ the bolt form of lock, positioned at one vertical edge, or in the case of an extremely wide grille positioned at both vertical edges, the walls adjacent these edges being provided with apertures which are adapted to receive the bolts of the locks. These locks are usually permanently placed in position by the manufacturer according to the customer's specification, and the grille must be individually designed as a whole to accommodate the desired form of lock and the required position of the lock with respect to the grille. These considerations add still further to the expense of the grille, not only in connection with the special design of the grille with respect to the position of the lock, but also in providing a pair of locks at opposite edges of the grille in order to secure both edges to the adjacent supporting framework.

In order to permit these locks to be unlocked from either side of the grille, it is customary to provide locks having keyholes accessible from each side and maintaining the lock itself in a permanent position. It is apparent that a tumbler lock, in which the key can be inserted from one side only of the lock, could not be employed in the prior form of grille, in case it were desired to unlock and lock the grille from either side of the grille.

The primary object of the present invention is to provide a grille having a construction by which both vertical edges of the grille may be temporarily locked in place by a simple mech-

anism, and controlled from a single locking unit positioned at any desired distance from either edge of the grille.

A further object is to provide a grille in which the lock is readily accessible from either side of the grille, and employing a lock of that type in which the key can be inserted only from one side of the lock, as in the case of the ordinary tumbler lock.

The invention will be better understood when the specification is perused in connection with the accompanying drawings.

In the drawings:

Figure 1 is an elevational view, in diagram, of the improved grille and the immediately surrounding support framework.

Figure 2 is a sectional view showing a portion of the grille and including a transverse section across one of the supporting uprights.

Figure 3 is an elevational view looking toward the inner surface of a typical support upright, showing the latch in section by which the grille can be rigidly secured to the upright.

Figure 4 is a view similar to Figure 3 but illustrating the effect of rotating the latch to obtain a locking action.

Figure 5 is a fragmentary elevational view of the grille immediately surrounding the lock and the latching members, showing the support uprights in section in order to illustrate a simple way in which adjustments of the latching position of the grille may be obtained.

Figure 6 is an enlarged fragmentary view looking toward the rear of the locking device, with the back plate removed to show the action of the cam.

Figure 7 is a sectional view taken along the line 7—7 in Figure 6, looking in the direction of the arrows. In this figure the cam is moved to a position such as to remove the bolt from the latching bar.

Figure 8 is a view similar to Figure 7, except that the bolt has been moved into locking position by rotation of the cam.

Figure 9 is a fragmentary view looking down on the top edge of the locking device, and showing a portion of the device in section.

Referring more particularly to Figure 1, the improved grille is formed essentially of metal strips, preferably of an aluminum alloy, and this strip material appears in two general shapes. One of the strip elements, indicated at 1, takes the form generally of a W with the horizontal portion indicated at 2 and the reverse curved portion indicated at 3, the ends of the strip being provided with diagonally extending portions 4 which terminate in short vertical portions 5. The immediately adjacent strip, generally designated 6, has a horizontal portion 7 which terminates at the right-hand end, as seen in Figure

2, in a vertical portion 8 and at the other end has a diagonal portion 9 which merges into a short vertical portion 10. The vertical portions 5 and 10, also the portion 8 of the strips are provided with apertures for receiving a rod 12 which may be formed of cold rolled steel.

The lower end of the grille supports a T-section plate 16 which is carried by a number of equi-distantly spaced straps, the latter having openings at their tops for receiving the lowermost rod 12, these straps being inserted in position between the downwardly extending portions 5, 10 of the strip units 1, 6. The lowermost surface of the plate 16 is adapted to rest on the floor immediately below the grille, as is well known in the art. It is apparent that in view of the pivotal connections between the vertical portions of the strip units 1, 6 and the rods 12, the grille as a whole is adapted to be rolled up.

When the grille has been moved to its lowermost position it may be desirable to prevent any unauthorized upward movement of the grille. For this reason it is necessary to install a suitable form of lock. A feature of my invention is the provision by which an improved locking device is installed, the arrangement being such that the device can be readily placed in any required position throughout the area of the grille by the manufacturer and as called for by the customer, without disturbing in any considerable degree the assembling operation of the various grille parts.

As shown more particularly in Figure 5, the lock itself is designated 29 and is pivotally mounted, as will be described hereinafter, within a metal frame 30. This frame is formed of two parts bolted together, as indicated at 31, and provided with extensions 32 which are positioned on opposite sides of a double thickness welded portion 7 of a pair of strip units 6. The extensions 32 are joined by a web 33 to the upright portions 34, the latter being spanned by horizontal bars 35, which together with the vertical portions 34 constitute a rectangular frame with a square opening 36 therein. The bars 35 are provided with circular openings 37, the upper one of which is adapted to receive a pivot rod 38 which is secured to the lock 29. The opening 37 in the lower horizontal bar 35 is of a size sufficient to permit a bolt 39 to reciprocate therethrough in a vertical direction. This bolt is secured to a slidable plate 40 (Figures 7 and 8) which forms part of the locking mechanism. The pivot rod 38 and the bolt 39 are in vertical alignment, and the lock 29 is of a size somewhat smaller than the opening 36, thus permitting the lock to be rotated in a horizontal plane for reasons which will appear hereinafter. The upper and lower bars of the frame 30 are provided with spaced wing elements 41 which are apertured to receive the rods 12.

The lower rod 12, as seen in Figure 5, carries at each end a latching device 42 the actuating element for which is constituted of a cylindrical member 43 keyed to the rod 12 and which has an enlargement 44 provided with a wing extension 45. There is a lug 46 integrally secured to the cylindrical enlargement 44, the position of the lug being such as to limit the rotational movement of the cylinder 43 when the wing extension 45 is pulled upwardly by hand. Under these conditions the cylinder 43 will rotate the rod 12 and the lug 46 will contact the lower surface of the horizontal member 35. The cylindrical enlargement 44 is provided with a bore 47 which is 75

adapted to receive the bolt 39 when the cylinder has been moved clockwise, as seen in Figure 8, and the lug 46 abuts the lower transverse member 35.

5 The lock 29 is preferably of rectangular configuration with its upper and lower surfaces slightly curved so as to facilitate the horizontal rotation of the lock within the frame members 30, 35. The vertical sides of the lock are also provided with curved surfaces, as indicated at e in Figure 9. In order to facilitate the vertical alignment of the lock within its frame, there may be provided a spring-urged catch 49 which fits into an opening 50 in one of the side frame members 10 30. It is apparent that as the lock 29 is rotated by hand on its pivots 38, 39 through 180 degrees, the catch 49 will fit into the groove 50 on the opposite side frame member 30 so that in both 15 30, 180 degrees apart, the front and rear faces of the lock are exactly in alignment with the front and rear faces of the frame members 30, 35.

20 The lock is preferably made of an aluminum alloy, formed by die casting, and is constituted of two parts 48 and 48' which are secured together by the screws 51. The lower portion of the two-part lock is cored out, as indicated at 25 52, to leave a hub 53 which has a large central opening 54. This opening is threaded, as indicated at 30 55, to receive the external threads of a tumbler block indicated at 56 (Figures 7 and 8) of any suitable and well known design. It is preferred that the tumbler block be of the type which receives the key only at one end, for 35 example, Corwin or Yale tumbler locks. Locks of this character are not readily susceptible to opening by unauthorized persons. As can best be seen in Figures 7 and 8, the lower part 48' of the lock block 29 is provided with a semi-circular opening 57 which is adapted to receive the bolt 39 and permit the latter to reciprocate vertically in the opening. This bolt is maintained in its vertical position by a semi-circular opening 58, directly opposite the opening 57 and formed in a web 59 which extends transversely inwardly from the other portion or cover 48 of the lock block 29.

40 There is a cam plate 60 secured to the right-hand face of the tumbler block 56 (Figures 7 and 8) by screws 61, this cam plate having a spiral groove 62 of a width to accommodate a pin 63. The cam plate is also held in position by a rectangular projection 64 which forms part of the tumbler mechanism contained within the block 56, so that as these tumblers are rotated, in a manner to be described, the rectangular projection 64 and the screws 61 will cause the cam plate to be rotated. The pin 63 is secured to the slidable plate 40 and projects inwardly from that plate to enter the groove 62. Consequently as the cam plate is rotated, on rotation of the tumblers, the pin 63 is caused eventually to move downwardly, carrying with it the plate 40 and causing the insertion of the bolt 39 in the opening 47 of the circular enlargement 44.

45 The lock block 56 is provided at its outer face with an opening 65 (Figure 5) for receiving a key 65' by which the tumblers are rotated. It is apparent that as the key is turned, and assuming that the wing projection 45 has been moved to such a position as to bring the opening 47 in alignment with the bolt 39, the tumblers cause the slidable plate 40 to move downwardly by the cam action and the bolt 39 to enter the opening 47, thus locking the rod 12

against rotation. When the key is moved to its unlocked position rotation of the tumblers moves the bolt 39 out of the opening 47, thus permitting the rod 12 to be rotated when the wing element 45 is moved downwardly.

Figure 7 shows the relative positions of the parts when the tumblers have been moved to their unlocked position and the wing projection 45 has been moved through an arc to the right as far as it will go, as determined by the abutment of the lug 46 against the lower bar 35. Figure 8 shows a locked condition in that the wing element 45 has been moved through an arc to its extreme left-hand position, thus rotating the rod 12, and held in that position by the entry of the bolt 39 into the opening 47. Consequently the rotation of the key in the lock block serves to permit the rod 12, which passes through the cylinder 43, to be either rotated by the wing element 45 or to be locked in a particular position depending on which way the key is turned. The locking effect can be obtained from either side of the grille because, as pointed out hereinbefore, the lock element 29 can be rotated in a horizontal direction at the pivots 38, 39 and is equally effective from the locking standpoint in either of these positions.

The latches 42, which will now be described, are so constructed that as the rod 12 which carries these latches is rotated in one direction the latches are loosened to permit the grille freely to slide in its end upright supporting frames, but when the rod is rotated in the other direction the latches secure the grille against upward or downward movement. As seen in Figure 2, these upright frames are provided at both sides of the grille and are preferably formed of a pair of sheet metal elements 66 secured to an angle iron 67 as by welding or bolting. The latter may be secured to any suitable part of the building, indicated at 68. The elements 66 are bent to form a housing 69 and having inwardly projecting extensions 70 which fit around certain portions of the latch members 42. The latches themselves may take the form of a pair of drums or hubs 71, spaced from one another and connected together by a pair of oppositely positioned bars 72 of substantially semicircular section.

The elements 71, 72 may be formed as a casting, the hubs 71 having openings therethrough of a D-shaped configuration which fit about a flattened portion of the rod 12 to give a key effect. Thus each unitary element 71, 72 is securely mounted against rotation on the rod 12. The shape of the bore in the hub member and the flattened shape of the rod 12 are such as to permit the composite latch element 71, 72 to slide along the rod 12 over the flattened portion thereof. However, the latch element is detachably secured to the rod by means of a cotter pin 73 at the end of each rod.

Each pair of extensions 70 of the sheet metal elements 66 is provided with a square-shaped cut-out 74, at a position directly in line with each latching element 42. At the position of each cut-out there is provided a box-shaped sheet metal member 75, of a length somewhat greater than the height of the cut-outs 74. The member 75 is provided with a slot 76 for receiving a screw 77 which enters one of the sides of the housing formed by the metal elements 66. By loosening the screw the element 75 may be moved in a vertical direction to an extent determined by the length of the slot 76. Each box-shaped element 75

75 has portions 75' (Figures 3 and 4) at its inner face which extend toward one another and cover the inner surfaces of the two outermost hub members 71. Thus these extending portions are positioned intermediate two adjacent hub members 71 of each latch.

There is an opening 78, preferably of circular configuration, in each pair of inwardly extending portions 75'. This opening has a diameter sufficient to accommodate the peripheral surfaces of each pair of bars 72 so that the rod 12 can be rotated and the opening 78 will accommodate the bars 72, as indicated in Figure 4. The space 79 between the inwardly projecting portions 75' is of a width somewhat greater than the depth of the bars 72 so as to permit these bars, and the rod 12 on which they are mounted, to be slid upwardly or downwardly through this space when the bars are in vertical alignment. In Figure 3 there is shown this position of the bars, and as illustrated the rod 12 can be moved upwardly through the space between the inwardly projecting portions of the box-like element 75 and then upwardly through the space 80 between the inwardly projecting extensions 70. As the rod 12 is rotated by moving the wing extension 45 to the left (Figure 7), the bars 72 take a horizontal position, and if it were attempted to move the rod 12 upwardly these bars would contact the peripheral edges of the circular openings 78. This condition is shown in Figure 4.

It will be understood that the main purpose for the box-like element 75 is to provide an adjustment of the height at which the rod 12 can be locked in place by the latches 42. This adjustment is controlled by the loosening of the screws 77 in the slots 76. Even if the element 75 were entirely removed, the square-shaped cut-outs 74 would still prevent free movement of the bars 72 upwardly when these bars are in horizontal alignment, because the upper surfaces of the bars would strike the upper edges of the cut-out 74. The element 75, therefore, restricts the upward movement of each latch 42 to a very limited length of travel, and in addition provides for adjustability of this limited position through the slot and screw arrangement 76, 77.

From the foregoing it is evident that I have disclosed an improved locking device by which a grille may be maintained in any predetermined vertical position with respect to the side frame uprights or guideways by means of latching members 42 which are controlled through the rotation of one of the grille rods 12. The latter may be manually rotated by the wing element 45 and locked in position by the turning of a key 65'. The locking mechanism is so constructed as to be accessible from either side of the grille, and its position with respect to the grille may be readily changed to accommodate customer's requirements by a simple modification of the grille elements immediately surrounding the lock. Practically all of the component parts of the grille, exclusive of the lock itself, may be formed initially from flat metal strips in readily obtainable shapes, and easily joined together either by welding or by bolting. The grille as a whole lends itself to be rotated on a drum, due to the pivotal connections formed at the rods 12.

It will be understood that I desire to comprehend within my invention such modifications as come within the scope of the claims and the invention.

Having thus fully described my invention, what

I claim as new and desire to secure by Letters Patent, is:

1. In combination, a grill, the area of which includes a number of spaced parallel rods, means for holding said rods in spaced parallel relation, vertical guides extending on each side of said grill and having slots slidably engaged by the ends of said rods, a lock, means for mounting said lock between any two rods lying adjacent to each other, means on at least one end of a rod and on the vertical guide therefor whereby when said rod is rotated said grill will be held in locked position, and latch means on said lock adapted to engage and hold said rod against rotation when said lock is in locked position.
2. In combination, a grill, the area of which includes a number of spaced parallel rods, means for holding said rods in spaced parallel relation, vertical guides extending on each side of said grill and having slots slidably engaged by the ends of said rods, a lock, means for mounting said lock between any two rods lying adjacent to each other, means on at least one end of a rod and on the vertical guide therefor whereby when said rod is rotated said grill will be held in locked position, and latch means on said lock adapted to engage and hold said rod against rotation when said lock is in locked position, said means on the end of the rod and its vertical guide including non-circular means on said rod and spaced circular enlargements on said vertical guide.
3. In combination, a grill the area of which includes a number of spaced parallel rods, means for holding said rods in spaced parallel relation, vertical guides extending on each side of said grill and having slots slidably engaged by the ends of said rods, a lock, means for mounting said lock between any two rods lying adjacent to each other, means on at least one end of a rod and on the vertical guide therefor whereby when said rod is rotated said grill will be held in locked position, and latch means on said lock adapted to engage and hold said rod against rotation when said lock is in locked position, said rod having a block mounted thereon adjacent said lock, said block having an opening, and said latch means including a bolt which is adapted to engage said opening when said rod is rotated to locking position and prevent further rotation thereof.
4. In combination, a grill the area of which includes a number of spaced parallel rods, means for holding said rods in spaced parallel relation, vertical guides extending on each side of said grill and having slots slidably engaged by the ends of said rods, a lock, means for mounting said lock between any two rods lying adjacent to each other, means on at least one end of a rod and on the vertical guide therefor whereby when said rod is rotated said grill will be held in locked position, and latch means on said lock adapted to engage and hold said rod against rotation position when said lock is in locked position, said lock including a frame, and means pivotally mounting said lock in said frame whereby access thereto may be obtained from either side of said grill.
5. In combination, a grill, the area of which includes a number of spaced parallel rods, means for holding said rods in spaced parallel relation, vertical guides extending on each side of said grill and having slots slidably engaged by the ends of said rods, a lock, means for mounting
- 5 10 15 20 25 30 35 40 45 50 55 60 65 70
- said lock between any two rods lying adjacent to each other, means on at least one end of a rod and on the vertical guide therefor whereby when said rod is rotated said grill will be held in locked position, and latch means on said lock adapted to engage and hold said rod against rotation when said lock is in locked position, said means on the end of a rod consisting of a pair of hubs and a pair of oppositely positioned bars, said hubs and bars being non-rotatably mounted on said rod.
6. In combination, a grill, the area of which includes a number of spaced parallel rods, means for holding said rods in spaced parallel relation, vertical guides extending on each side of said grill and having slots slidably engaged by the ends of said rods, a lock, means for mounting said lock between any two rods lying adjacent to each other, means on at least one end of a rod and on the vertical guide therefor whereby when said rod is rotated said grill will be held in locked position, and latch means on said lock adapted to engage and hold said rod against rotation position when said lock is in locked position, said means on the end of a rod consisting of a flattened portion thereon, a pair of hubs and a pair of oppositely positioned bars, on said rod end, said hubs having openings therethrough of square configuration, which fit about said flattened portion to provide a key effect.
7. In combination, a grill, the area of which includes a number of spaced parallel rods, means for holding said rods in spaced parallel relation, vertical guides extending on each side of said grill and having slots slidably engaged by the ends of said rods, a lock, means for mounting said lock between any two rods lying adjacent to each other, means on at least one end of a rod and on the vertical guide therefor whereby when said rod is rotated said grill will be held in locked position, and latch means on said lock adapted to engage and hold said rod against rotation when said lock is in locked position, said means on the end of a rod consisting of a flattened portion thereon, a pair of hubs and a pair of oppositely positioned bars, on said rod end, said hubs having openings therethrough of square configuration, which fit about said flattened portion to provide a key effect, and means for detachably securing said hubs and bars to said rod.
8. In combination, a grill, the area of which includes a number of spaced parallel rods, means for holding said rods in spaced parallel relation, vertical guides extending on each side of said grill and having slots slidably engaged by the ends of said rods, a lock, means for mounting said lock between any two rods lying adjacent to each other, means on at least one end of a rod and on the vertical guide therefor whereby when said rod is rotated said grill will be held in locked position, and latch means on said lock adapted to engage and hold said rod against rotation when said lock is in locked position, said means on the end of a rod consisting of a flattened portion thereon, a pair of hubs and a pair of oppositely positioned bars, on said rod end, said hubs having openings therethrough of square configuration, which fit about said flattened portion to provide a key effect, and a box-shaped member mounted in said vertical guides, said box-shaped member having extensions which cover portions of the surfaces of certain of said hub members in one position of the grill.

EDWARD H. McCLOUD.
